UNITED STATES PATENT OFFICE.

CHARLES ED. HAVILAND, OF LIMOGES, FRANCE.

DESIGN FOR A DISH.

SPECIFICATION forming part of Design No. 20,631, dated March 24, 1891.

Application filed February 24, 1891. Serial No. 382,636. Term of patent 14 years.

To all whom it may concern:

Be it known that I, CHARLES EDWARD HAVILAND, a citizen of the United States, residing at the city of Limoges, in the Republic of France, have invented and produced a new and original Design for a Dish or other Article, of which the following is a specification, reference being had to the accompanying drawings, forming part thereof.

10 Figure 1 is a side elevation of a dish, showing my design; and Fig. 2 is a vertical section of same on the dotted line 2 2 of Fig. 1.

In the drawings, A designates the dish, and B the cover therefor, the latter having at the 15 center of its upper surface the handle C in the outline of a conventionalized head of cauliflower, with its leaves D resting upon the upper surface of said cover. The rim or outer edge of the cover B is provided with

20 the ornamental scrolls E F G H, the scrolls E F G being in relief and the scrolls H in in-

taglio. The bowl A has upon opposite sides the handle I, formed by the ornamental conventionalized foliate scrolls J, and said bowl rests upon four legs or supports K, having the 25 contour of conventionalized scrolls lettered L. The upper outer edges of the bowl A are ornamented with the conventionalized scrolls M N O P, which are similar in all respects as to relief and intaglio to the scrolls E F G H, 30 formed upon the outer portions of the cover B.

What I claim is—

The design for a dish or other article, substantially as shown and described.

Signed at the city of Limoges, in the Republic of France, this 10th day of February, 1891.

CHARLES ED. HAVILAND.
